MAGNETIC RECORDING AND REPRODUCING

Semi Joseph Begun, Cleveland Heights, Ohio, assignor to Magnetone Inc., Cleveland, Ohio, a corporation of Ohio

Application July 21, 1943, Serial No. 495,801

7 Claims. (Cl. 179—100.2)

This application is a continuation-in-part of applicant's application Serial No. 370,417, filed December 16, 1940.

This invention relates to magnetic recording and reproducing, and it has among its objects improved novel magnetic recording and reproducing methods and arrangements which are particularly useful for applications, such as time delay systems, although the various features of the invention are not limited thereto.

The foregoing and other objects of the invention will be best understood from the following description of exemplifications thereof, reference being had to the accompanying drawing which is a diagrammatic view of the circuits and the operating elements of an endless magnetic recording arrangement designed for the supervision of the contents of signal sequences, such as broadcasts, or, in general, messages which are transmitted over a transmission channel.

Referring to the drawing, a source of signal energy, such as a microphone MC, delivers its output to an amplifier IA, the output of which, instead of being impressed directly on a modulator and radio broadcast transmitter TR, is supplied to a recording head 4—R of an endless magnetic recording carrier shown in the form of a long endless magnetic tape 31 driven at uniform speed in clockwise direction, for instance.

The signal recorded on each element of the moving endless tape remains thereon until, after a predetermined supervision time delay, the recorded element of the endless tape reaches a playback head 4—P, the output coil of which is connected to the modulator and radio broadcast transmitter TR, so as to bring about the broadcast of the message from the microphone in the same way as if it had been directly supplied to the radio broadcast transmitter, but with the predetermined supervision time delay.

An obliterating head shown in the form of a permanent magnet, is placed before the recording head 4—R to assure that each carrier element reaching the recording head 4—R is ready to receive a new recording. The equipment thus far described, constitutes a signal transmission channel of a signal transmission system including an endless magnetic carrier and signal transducing means associated therewith so that messages supplied by the signal input means, such as the microphone MC, are transmitted to signal output means, such as the radio transmitter TR, with a predetermined time delay.

The equipment for supervising or censoring the transmitted message has a sequence of alike su-

pervising stations, a sequence of two censoring stations CA, CB being shown for the sake of simplicity. Each censoring station is provided with a set of four push button switches K, L1, L2, L3, 5 and with headphones 81, a signaling lamp 82 and auxiliary switching elements for performing the various operations as explained hereinafter.

Assuming, for instance, that the supervising station CA is activated, and keeps on supervising 10 the transmitted message, the supervisor keeps the push button switch L1 of his station actuated and the headphones 81 of his station are connected through the switch contacts to an output lead 83 from the amplifier IA, so as to enable 15 him to listen to the transmitted message as it is being recorded on the endless magnetic tape 31 for subsequent transmission, after the time delay determined by the location of the recording head 4—R and the pickup head 4—P along the path 20 of motion of the endless magnetic tape, for instance, one or two minutes, to the radio broadcast transmitter TR.

Upon releasing the push button L1, and actuating the push button L2, the censor at each station may connect his headphones to the output 25 lead of a playback amplifier AM—1 upon which is impressed the output of a playback head located on an intermediate portion of the tape so as to enable the censor, if, after listening to the transmitted message, he realizes that it contains 30 objectionable matter, to pickup the starting phrase of the message so as to enable him to cancel the entire objectionable message before it can be transmitted from the main playback head 4—P to the radio broadcast transmitter TR.

After having thus picked up the starting phrase 35 of the objectionable message, the censor has merely to release the push button L2, and by actuating push button L3, connect his headphones 40 81 to the output lead from amplifier AM—2 which amplifies the output of a third playback head 4—P3 placed a distance ahead of the main playback head 4—P, and as soon as he hears the initial phrase of the objectionable message, he 45 has merely to push button K which completes a circuit sending an obliterating current to the obliterating head 4—O3 placed ahead of the main playback head 4—P, thereby cancelling the message recorded on the tape and preventing its 50 transmission when the elements of the tape on which it was recorded pass through the main playback head 4—P.

In order to make such censoring system effective, a sequence of at least two censoring stations, 55 such as indicated at CA, CB, must be provided

so that while one censor traces an objectionable message and attends to its being cancelled, the other censor may attend to the censoring of the further part of the matter that is being broadcasted. Under normal transmission of a broadcast, only one censor has to watch the transmission of the broadcast.

In order to indicate to the censor that it is his duty to listen in, the signaling lamp of the proper station, for instance, station A in the case shown, is lighted by a circuit completed through the contact of a stepping switch 88 having an operating coil 87, which, upon energization, advances the contact of the stepping switch one step, thereby cutting out the signal lamp of station A and lighting up the signal lamp of station B, indicating to the censor of the latter station that it is his duty to watch the transmitted message by closing his push button switch L1.

With this arrangement, censor A, whose signaling lamp 82 is lighted and has his push button L1 operated to listen to the transmitted message, on noticing that the message contains objectionable matter, merely releases the push button L1 and actuates the push button L2, which immediately connects his headphone to the intermediate playback head 4-P2 for enabling him to pickup the starting phrase of the objectionable message. On closing his push button switch L2, the censor at station A also completes a circuit, including the normally closed contacts of an interlocking auxiliary relay 88 to the operating coil 87 of the stepping switch, thereby advancing it to the next stop in which his own signal lamp 82 is extinguished and the signal lamp 82 of the other censor is lighted up, whereupon the censor B actuates his push button switch connecting his own headphones to the amplifier IA for watching the transmitted message.

Each of censor stations CA, CB is shown provided with interlocking means for assuring that when one censor station starts tracing the objectionable matter and attends to its cancellation, only one signaling operating operation is transmitted to the other, or next, censor station to start listening in to the messages that are being transmitted. In the arrangement shown, the interlocking means of each station is formed by the time delay relay 88 arranged so that—when either one of switches L2 or L3 is actuated to listen in to the recorded objectionable message—there is established not only an instantaneously operative circuit to the stepping coil 87 of the stepping relay 88, which lights up the signal lamp of, or otherwise activates the next censoring station, such as CB, but also an interlocking circuit to the time-delay interlocking relay 88, which opens its contacts after a predetermined time delay, thereby interrupting the signaling circuit to the stepping magnet through which the next station has just been activated. The interlocking relay 88 of each censoring station is designed to have a time delay in opening and a time delay in closing of a sufficiently long time to assure that during the time interval between releasing the listening in switch L2 of pickup head 4-P2 and actuation of the listening switch L3 of the next pickup head 4-P3, the contacts of the switch 88 will remain open and prevent transmission of another activation signal to the next censoring station.

The censor at station A, upon having picked up the beginning phrase of the objectionable message, will release his push button L2 and actuate his push button switch L3 so as to connect his

head phone to the playback head 4-P3 and be ready to cancel the message as soon as he hears the initial phrase of the message in question, whereupon he actuates his cancelling button switch K which completes a circuit sending an obliterating current to the obliterating head 4-O3.

Locking means are also provided for preventing accidental obliterating of a message that is being transmitted. In the arrangement shown, the obliterating push button switches K are normally held locked by a locking relay 91 having a latch arm 92 with a latch projection 93 engaging a latch projection 95 of the obliterating switch K, so as to normally prevent it from being actuated to send on obliterating current through the obliterating head 4-O3. The locking relay is arranged to be energized and operated to release the obliterating switch K from its locked position by one of the contacts of the push button switch L3, when the latter is actuated by the censor when he is about to pickup the initial phrase of the objectionable message and effect its obliterating in the manner described above.

The contact arm of the obliterating switch K is biased to return when released to its open position, and the latch arm 92 is normally biased to return to the locking position shown, the latch projections 93, 95 of the locking means and their associated elements being so shaped and arranged that the contact arm of the obliterating switch K is free to return to its open position shown whenever it is released, no matter whether the switch L3 is in the non-actuated position shown, or in its actuated position.

The foregoing arrangement provides thus a foolproof censoring system, which prevents undesirable interference with the transmitted message and permits tracing of an objectionable part of the message while its transmission is delayed, as well as the selective obliterating of the objectionable message part before it is being transmitted.

Obviously, a larger number of message tracing playback heads, such as 4-P2 may be provided for enabling the censor to pick up different parts of the message which are stored in the endless tape, while they are being advanced from the recording head 4-R, during the time interval of the time delay cycle, to the point where they are picked up by the playback head 4-P for delivery to the radio broadcast transmitter TR.

The supervising or censoring arrangement described above represents a signal transmission channel formed by the endless magnetic carrier 81 and the associated transducing means and constituting an interconnection between the signal input means, represented by the microphone MC, and the signal output means, represented by the radio transmitter TR, for transmitting through the channel and delivering to the transmitter a series of signal sequences supplied by the microphone MC. The signal transducing means associated with the carrier are formed of the various transducer elements 4-R, 4-P2, 4-P3, 4-O3, 4-P, 4-O located along the path of the carrier for recording, reproducing and obliterating, respectively, the signal sequences recorded on the carrier as it moves past the transducing means.

At least one signal recording element, represented by the recording element 4-R, serves to record on a portion of the endless carrier moving past it the signal sequence as it is being supplied thereto by the microphone MC. Each element of

the recorded signal sequence is reproduced with a predetermined time delay by the transmission pickup element 4-P which supplies reproduced signals to the transmitter TR.

In order to supervise the transmission of the signal sequence, the endless signal carrier is also provided with supervising means formed of a supervising set-up which, in the arrangement shown, is composed of two pickups 4-P2 and 4-P3, the two pickup elements 4-P2 and 4-P3 being located along spaced intermediate portions of the path of the endless carrier.

The supervising means also include at least two supervising set-ups, represented by the supervising set-ups CA, CB, each supervising set-up including switches L1, L2, L3 for selectively translating the recorded message either as directly supplied by the microphone or as reproduced by one of the pickups into an observable sound signal sequence reproduced by the translating means, represented by the receiver 81.

In addition, each of the supervising set-ups includes canceling means provided with an obliterating element located along a portion of the carrier path extending between the transmission pickup element 4-P and the next preceding pickup element 4-P3 for enabling selective obliterating of the recorded signal before it is picked up by the transmission pickup element 4-P.

The supervising means are also provided with activating means automatically operative when an active supervising set-up starts to trace the objectionable message to activate another supervising set-up by giving it a signal to take over the further supervising action, the activating means being represented by the selector switch 86 and the signaling lamps 82 which are automatically actuated when one of the supervising set-ups stops the supervising action and starts tracing the objectionable message, and brings about its cancellation.

The automatic activating means are also provided with automatic locking means which are operative in response to the actuation of one of the switches L2, L3 associated with the translating means of the supervising set-up for preventing sending out of more than one activating signal to another supervising set-up of the supervising equipment, the interlocking means being represented by the time-action relays 88 and the associated circuit elements.

Each supervising system is also provided with preventing means, represented by the relay 91 and the interlocking elements 92, 93, 95 associated with the supply of current to the obliterating current 4-O3 so as to prevent the obliterating of the recorded sound sequence carried by the elements of the carrier as they move along the path from the recording element 4-R to the transmission element 4-P, unless the supervising means have been activated to reproduce the signal by a pickup element, such as pickup element 4-P3 located along the path of the carrier preceding the portion along which the transmission pickup 4-P is located.

In accordance with the invention, each supervising setup is also provided with automatic canceling means having a cancellation starting element actuatable when the initial operation of the characteristic signal sequence supplied to the signal carrier is observed and a cancellation stopping element actuatable when the end portion of a characteristic signal sequence which is to be cancelled is observed for causing the canceling means to be automatically operated causing the

cancelling means to automatically obliterate the objectionable signal sequence which has been recorded on the carrier and has been reproduced by a selected pickup element during an interval between the actuation of the cancellation starting element and the actuation terminating element.

The automatic canceling means may utilize any form of known time-action means which are so designed as to perform a timing action correlated to the time during which a carrier element moves from one of the pickup elements—which is being used to trace the message to be cancelled—to the obliterating element 4-O3.

In order to prevent the discontinuity formed by a soldering joint, such as 39, from interfering with the censoring operation, a censoring system of the invention may be built as follows: The endless magnetic signal carrier is arranged to move along a path formed of a plurality of path sections such as indicated in Fig. 1 of my application Serial No. 370,417, filed December 16, 1940—and represented there by the three sections of the carrier associated with the recording heads RA, RB, RC, respectively.

Each of the carrier path sections is in turn provided with a complete set of transducing elements, such as represented by the transducing elements 4-R, 4-P2, 4-P3, 4-O3, 4-P and 4-O shown in the drawing of the present application and interconnected in the same manner so that each signal sequence supplied by the microphone MC is simultaneously recorded by two recording elements 4-R on two different sections of the carrier path, respectively, and similarly reproduced and supplied to the radio transmitter TR from two transmission pickup elements 4-P associated with the two carrier path sections.

Each of the carrier path sections is also provided with automatic signal suppression means associated with a switch 51 actuated by a carrier signal 39 in the same manner as corresponding elements 31, 51 of my aforesaid application Serial No. 370,417 serve to suppress the reproduced signal that is to be transmitted when a discontinuity of the carrier passes through the transmission pickup element.

It will be apparent to those skilled in the art that the novel principles of the invention disclosed herein in connection with specific exemplifications thereof will suggest various other modifications and applications of the same. It is accordingly desired that in construing the breadth of the appended claims they shall not be limited to the specific exemplifications of the invention described herein.

I claim:

1. In a signal transmission system having signal input means for supplying signal sequences and signal output means for delivering the supplied signal sequences: a signal transmission channel interconnected between said signal input means and signal output means and including an endless magnetic signal carrier for magnetically recording thereon and reproducing therefrom signals while the elements of said carrier are impelled along a predetermined carrier path; signal transducing means including a set of transducing elements located along said path for recording or reproducing a signal sequence while said carrier moves past said transducing means; said set of transducing elements including at least one recording element located along one portion of said path for recording on the carrier signal sequences supplied by the input means

and transmission means having a transmission pickup element located at another portion of said path for reproducing from said carrier signals recorded thereon by said recording element with a predetermined time delay, and means for transmitting the reproduced signals to said output means; supervising means including a supervising set-up for supervising the signal sequences of said source transmitted through said channel; said supervising set-up including at least one intermediate pickup element located along an intermediate portion of said path; translating means including selectively operative actuating means for selectively translating the signals reproduced by said intermediate pickup element into an observable signal; and canceling means for obliterating the signal recorded on said carrier before it is reproduced by said transmission pickup element; said canceling means including an obliterating element located along a portion of said path extending between said transmission pickup element and the preceding pickup element, said canceling means including means for performing a timing action correlated to the time during which a carrier element moves from one of the pickup elements to the obliterating element and having a cancellation starting element actuatable when the initial portion of a characteristic signal sequence is observed and a cancellation stopping element actuatable when the end portion of a characteristic signal sequence is observed, for causing said canceling means to obliterate the signal sequence which has been recorded on said carrier during the interval between the actuation of said starting element and the actuation of said terminating element.

2. In a signal transmission system having signal input means for supplying signal sequences and signal output means for delivering the supplied signal sequences: a signal transmission channel interconnected between said signal input means and signal output means and including an endless magnetic signal carrier for magnetically recording thereon and reproducing therefrom signals while the elements of said carrier are impelled along a predetermined carrier path; signal transducing means including a set of transducing elements located along said path for recording or reproducing a signal sequence while said carrier moves past said transducing means; said set of transducing elements including at least one recording element located along one portion of said path for recording on the carrier signal sequences supplied by the input means and transmission means having a transmission pickup element located at another portion of said path for reproducing from said carrier signals recorded thereon by said recording element with a predetermined time delay, and means for transmitting the reproduced signals to said output means; supervising means including a sequence of at least two supervising set-ups for supervising the signal sequences of said source transmitted through said channel; each of said supervising set-ups including at least two intermediate pickup elements located along spaced intermediate portions of said path; translating means including selectively operative actuating means for selectively translating the signals reproduced by said intermediate pickup elements into an observable signal; and canceling means including an obliterating element located along said path between said transmission pickup element and the preceding pickup element for

obliterating the signal recorded on said carrier before it is reproduced by said transmission pickup element; and signalling means interconnecting said two set-ups operative in response to the actuation of one set-up for signalling its actuation to the other set-up.

3. In a signal transmission system having signal input means for supplying signal sequences and signal output means for delivering the supplied signal sequences: a signal transmission channel interconnected between said signal input means and signal output means and including an endless magnetic signal carrier for magnetically recording thereon and reproducing therefrom signals while the elements of said carrier are impelled along a predetermined carrier path; signal transducing means including a set of transducing elements located along said path for recording or reproducing a signal sequence while said carrier moves past said transducing means; said set of transducing elements including at least one recording element located along one portion of said path for recording on the carrier signal sequences supplied by the input means and transmission means having a transmission pickup element located at another portion of said path for reproducing from said carrier signals recorded thereon by said recording element with a predetermined time delay, and means for transmitting the reproduced signals to said output means; supervising means including a sequence of at least two supervising set-ups for supervising the signal sequences of said source transmitted through said channel; each of said supervising set-ups including at least two intermediate pickup elements located along spaced intermediate portions of said path; translating means including selectively operative actuating means for selectively translating the signals reproduced by said intermediate pickup elements into an observable signal; canceling means including an obliterating element located along said path between said transmission pickup element and the preceding pickup element for obliterating the signal recorded on said carrier before it is reproduced by said transmission pickup element; signalling means interconnecting said two set-ups operative in response to the actuation of one set-up for signalling its actuation to the other set-up; and activating means operative in response to the actuation of the translating means of one supervising set-up for supplying an activating signal to another supervising set-up.

4. A signal transmission system as defined by claim 3, which has interlocking means for preventing the transmission of more than one activating signal by a supervising set-up while tracing a signal sequence recorded thereon.

5. A signal transmission system as defined by claim 3, which has preventing means operative to prevent the operation of the canceling means while the translating means are inactive next to said transmission pickup element.

6. A signal transmission system as defined by claim 3, characterized by the fact that the canceling means include means for performing a timing action correlated to the time during which a carrier element moves from one of the pickup elements to the obliterating element and having a cancellation starting element actuatable when the initial portion of a characteristic signal sequence is observed and a cancellation stopping element actuatable when the end portion of a characteristic signal sequence is observed,

for causing said canceling means to obliterate the signal sequence which has been recorded on said carrier during the interval between the actuation of said starting element and the actuation of said terminating element.

7. In a signal transmission system having signal input means for supplying signal sequences and signal output means for delivering the supplied signal sequences: a signal transmission channel interconnected between said signal input means and signal output means and including an endless magnetic signal carrier for magnetically recording thereon and reproducing therefrom signals while the elements of said carrier are impelled along a predetermined carrier path; said path having at least two path sections; signal transducing means including one set of transducing elements located along one section of said path and at least one other set of transducing elements located along another section of said path for recording or reproducing a signal sequence while said carrier moves past said transducing means; each of said sets of transducing elements including at least one recording element located along one portion of said path section for recording on the carrier signal sequences supplied by the input means

and transmission means having a transmission pickup element located at another portion of said path section for reproducing from said carrier signals recorded thereon by said recording element with a predetermined time delay, and means for transmitting the reproduced signals to said output means; supervising means including a sequence of at least two supervising set-ups for supervising the signal sequences of said source transmitted through said channel; each of said supervising set-ups including at least one intermediate pickup element located along an intermediate portion of said path section; translating means including selectively operative actuating means for selectively translating the signals reproduced by said intermediate pickup elements into an observable signal; and canceling means including an obliterating element located along said path section between said transmission pickup element and the preceding pickup element for obliterating the signal recorded on said carrier before it is reproduced by said transmission pickup element and signalling means interconnecting said two set-ups operative in response to the actuation of one set-up for signalling its actuation to the other set-up.

SEMI JOSEPH BEGUN.
